AUTOMATIC STATION SELECTOR

Roscoe Bowerman, Los Angeles, Calif.

Application March 12, 1934, Serial No. 715,156

12 Claims. (Cl. 250—20)

This invention relates to automatic station selectors.

The general object of this invention is to provide an improved device for automatically tuning a radio receiving set.

A further object is to provide a tuning control which may be set to select certain desired stations at predetermined times each day and to select other stations at predetermined other times.

Another object is to provide an improved automatic tuning mechanism for a radio set which will operate continuously without resetting or rewinding.

Other objects and the advantages of this invention will be apparent from the following description taken in connection with the accompanying drawings wherein:

Fig. 1 is a side elevation of my improved radio control;

Fig. 2 is a top plan view of my control;

Fig. 3 is an enlarged fragmentary section of my device;

Fig. 4 is a section taken on line 4—4 of Fig. 3;

Fig. 5 is an enlarged section taken on line 5—5 of Fig. 10 showing the reset mechanism;

Fig. 6 is a section taken on line 6—6 of Fig. 5;

Fig. 7 is an enlarged section taken on line 7—7 of Fig. 3 showing the motor reversing switch;

Fig. 8 is a side elevation of the shifting mechanism;

Fig. 9 is an enlarged section taken on line 9—9 of Fig. 10;

Fig. 10 is a section taken on line 10—10 of Fig. 3;

Fig. 11 is an enlarged section of the clock switch;

Fig. 12 is a section taken on line 12—12 of Fig. 11;

Fig. 13 is a front elevation of my time switch contact mounting;

Fig. 14 is a section taken on line 14—14 of Fig. 4;

Fig. 15 is an enlarged section of my radio control switch;

Fig. 16 is an enlarged bottom view of one of my time pins;

Fig. 17 is a section taken on line 17—17 of Fig. 10; and,

Fig. 18 is a wiring diagram of my radio control.

Referring to the drawings by reference characters I have indicated my radio receiver control generally at 10 (Fig. 1). As shown the control device 10 includes a circular table body portion 11 mounted on an upright standard 12 which is secured to suitable legs 13. The body 11 includes

a bottom member 14 on which a cylindrical wall member 15 is peripherally mounted. On the upper part of the cylindrical wall member 15 I mount a partition 16 which extends across the table body 11. A cylindrical support 17 is peripherally mounted on the partition 16 and supports an annular flange 18 on which is peripherally mounted a cylindrical top support 19. The body 11 further includes segmental covers 20 each hinged as at 21 to the cylindrical support 19 and provided with suitable means as thumb holes 22. The covers 20 are rabbeted as at 23 to receive segmental panes of glass 24.

Mounted at the center of the partition 16 I provide an upright standard 25 which is secured in place by bolts 26. The standard 25 terminates in a boss 27 which removably secures a lid 28 in place flush with the covers 20. The under periphery of the lid 28 is rabbeted as at 29 to receive a depending skirt 30 which is secured thereto. Cover stops 31 are secured to the skirt to hold the covers 20 in proper position.

Mounted on the partition 16 and coaxial with the support 25 I provide a circular bearing support 32. Rotatably positioned about the standard 25 I provide a control disk 33 made of electrical insulation material which is supported by bearings 34 mounted on the flange 18. An upstanding circular drum 36 is mounted upon the disk 33 and adapted to rotate therewith. On the drum 36 I provide a plurality of sets of condenser rotor plates 37 shown as four in number in the accompanying drawings.

On the standard 25 I fixedly secure a hub 38 upon which are secured a plurality of sets of condenser stationary plates 39 which are inter-spaced with the rotor plates 37. Thus it is seen that when the control disk 33 is rotated the capacity between the rotor and stator plates will increase for the first 45° rotation, decrease for the next 45° rotation, then increase for the next 45° rotation, and so on, increasing and decreasing four times each rotation.

A radio receiving set 40 is positioned in the body portion 11 below the partition 16. The sets of condenser plates 37 and 39 are suitably connected to the receiving set 40 as by wires 41 and 42, as shown in Fig. 18, and is adapted to serve as the station selector. Thus as the control disk rotates to predetermined positions the receiving set is tuned to predetermined frequencies.

To resiliently urge the control disk 33 to rotate in a counter-clockwise direction I provide a spring 43 having one end secured to the standard 25 by a screw 44 and having the other end se-

cured to a drum 45 which is in turn secured to the underside of the control disk, 33.

To rotate the control disk 33 to a wound position I provide a rewind motor 46 mounted on the partition 16. This motor includes a shaft 47 having a friction pulley 48 secured thereto which engages the outer surface of the drum 45. For actuating the rewind motor 46 I provide a switch 49 which includes an operating arm 50. The arm 50 is adapted to be actuated by an arm 51 secured on the disk 33.

On the control disk 33 I provide a plurality of outer arcuate slots 52 and a plurality of inner arcuate slots 53 (see Fig. 4) in which are movably positioned a plurality of knurled station selector buttons 54. The buttons 54 are threaded as at 55 to receive a nut 56 (see Fig. 5). The slots 52 and 53 at the lower edge include a rabbet 57 on each side which is engaged by a portion of the nut 56. Each button 54 is apertured as at 58 to receive a stop pin 59 which includes a knurled head 60 and an outwardly extending reset arm 61. The nut 56 includes a shoulder 62 against which the arm 61 is adapted to be positioned.

To allow the control disk 33 to intermittently rotate as to be hereinafter described I provide an oscillating stop plate 63 (Figs. 3, 7 and 8) which is supported by uprights 64 which are grooved as at 65 to receive the plate 63. The uprights 64 are suitably mounted to the partition 16. For shifting the plate 63 I provide a reversible motor 66 which includes a shaft 67 which is connected by a coupling member 68 to a drive shaft 69 positioned in bearings 71 integral with the uprights 64. The portion of the shaft 69 between the uprights 64 is threaded as at 72. An internally threaded lug 73 is positioned on the threads 72 and includes upwardly extending wings 74 secured to the plate 63 as by rivets 75.

Adjacent the shaft 69 I provide a snap-over motor reversing switch 76 mounted on the partition 16. The switch 76 includes a suitable housing 77 on which a switch arm 78 is pivotally mounted as at 79. A spring 80 has one end secured to the lower portion of the housing 77 and the other end secured to the upper end of the arm 78 and is adapted to resiliently hold the switch arm 78 in either a right or left position. The switch arm 78 includes a pair of contact bars 81 and 82 which are adapted to bridge pairs of contacts 83 and 84, and 85 and 86, respectively, when in one position and to bridge pairs of contacts 87 and 88, and 89 and 90, respectively, when in the other position. A switch operating bar 91 is secured to the lug 73. The operating bar 91 includes outstanding ends 92 which are adapted to engage the arm 78 to actuate the switch 76.

Circumferentially arranged in the annular flange 18 I provide a plurality of time pins 93 which include polygonal middle portions 95, and cylindrical lower portion 96. Below the flange 18 an annular contact support 97 made of insulating material is positioned. The support 97 is provided with a plurality of polygonal apertures 98 which are spaced to receive the portions 95 and 96 of the pins 93. Adjacent each aperture 98 I provide a pair of contacts 99 and 100. The pin 93 is adapted to move vertically in an aperture 101 in the flange 18.

The pins 93 each include a quadrant shaped contact plate 102 (Fig. 17) which is adapted to bridge the contacts 99 and 100 mounted in the support 97. Reset arms 103 are also provided in the pins 93.

Mounted in the wall member 15 I provide a

clock 104 which includes a shaft 105 which is driven at the rate of one revolution every twenty-four hours. A disk 106 is secured to the shaft 105 and is adapted to rotate therewith. Back of the disk 106 I provide a contact bracket 107 provided with two circular rows of contacts 108 and 109 (see Fig. 11), and a circular ratchet rack 110.

Mounted on the disk 106 I provide a housing 113 having a recess 114 therein in which bar 115 is slidably mounted. The bar 115 is normally urged towards the center of the disk by a coiled spring 116 one end of which engages the bar 115 and the opposite end a screw plug 117 provided to close the recess 114. Mounted on the bar 115 I provide a contact blade 118 which extends out of the housing 113 through an aperture 119 therein. As the disk 106 rotates the blade 118 is caused to rise on the teeth of the ratchet 110 and then descend making a momentary connection between successive pairs of the contacts 108 and 109.

To turn off the radio set when it is no longer desired to have it play I provide a switch 120 (see Figs. 14 and 15) mounted on the drum 32 and a similar switch 121 mounted on a bracket 122. These switches are operated by a plurality of stop pins 123 which are mounted on the disk 33 on the same radius as the selector pins 52 (see Figs. 14, 15 and 16). As shown the stop pins 123 are mounted in apertures 124 in the disk 33 and in apertured plugs 125 which are secured to the disk 33 and include shoulders 126 similar to the shoulder 62 of the nuts 56. Each of the stop pins 123 includes a reset arm 127 and a quadrantal switch operating arm 128.

Each of the switch members 123 includes a rigid contact arm 129 and a flexible contact arm 130. As shown in Fig. 18 the contact arms 130 are connected by a wire 131 and one of the contact arms 129 is connected by a wire 132 to a source of electrical energy which is shown as a battery 133 while the other contact arm 129 is connected by a wire 134 to one power terminal of the radio set 40. The other power terminal of the radio set is connected by a wire 135 to the opposite side of the battery 133. The wire 135 preferably has a control switch 136 interposed therein between the radio set and the battery.

From the foregoing it will be apparent that when the switch operating arm 128 of one of the stop pins 123 engages the resilient contact arm 130 of one of the switches 120 and moves it out of engagement with its associated rigid contact arm 129 the power circuit from the battery 133 to the radio set will be broken whereupon the radio set will cease to operate until the stop pin 123 passes the switch 120 thereby allowing the resilient contact arm 130 to again engage its associated contact arm 129.

The snap-over switch 76 is suitably wired to the motor 66 so that in one position of the contact arms current goes through the motor field to operate the motor in one direction and when the contact arms are in the other positions the current is reversed through the motor field to operate the motor in a reverse direction. As shown the field contacts 84 and 98 are connected by wires 135 to one field terminal of the motor 66 and the other field contacts 85 and 87 are connected by wires 136 to the other field terminal of the motor. The brush contacts 83 and 88 are connected by wires 137 to one of the motor brushes and the brush contacts 86 and 89 are connected by wires 138 to the other motor brush. Electric current is directed by a wire 139 from the wire 136 to one

terminal of the motor 66. The other terminal of the motor 66 is connected by a wire 140 to one end of an electro-magnetic coil 141, the opposite end of which is connected by a wire 142 to a contact 143 and by a wire 144 to each of the contacts 100. The associated contacts 99 are each connected by a wire 145 to one of the contacts 109 of the clock switch. The track 108 of the clock switch is connected by a wire 146 to the wire 132.

Adjacent the coil 141 I provide a pivoted arm 147 having an armature plate 148 and a contact 149 thereon. The contact arm 147 is connected by a wire 150 to the wire 146. At one predetermined point on the clock switch I provide a contact member 151 which is connected by a wire 152 to one terminal of the rewind motor 104, the other terminal of the motor being connected by a wire 153 to one terminal of the switch 49 and the other terminal of the switch is connected by a wire 154 to the wire 139. The clock 104 is shown as operatively connected to the battery 133 by wires 155 and 156.

To cause operation of the radio set regardless of the condition of the control device 10 I provide a switch 157, one terminal of which is connected by a wire 158 to the wire 132 and the other terminal is connected by a wire 159 to the wire 133.

When the device is first set for operation the station selector buttons 60 are positioned on the disk 33 so that when they are in a position adjacent the plate 63 the condenser is in the correct position to tune in the correct station. After correctly positioning the selector pins 59 the bolts 54 are screwed into the nuts 56 to firmly clamp them in position on the disk 33. When it is desired to have a certain station play at a predetermined time the selector pin representing the desired station is moved downwardly so that the end of the pin 59 projects below the upper edge of the plate 63 and at the same time the pin 93 indicating the time it is desired to have the station play is pushed down so that its contact arm 101 bridges the associated contacts 99 and 100 thus closing the circuit at that point from the wire 144 to the wire 145.

Thus when the contact blade 118 of the clock switch makes contact between the contact ring 108 and the contact 109 connected by the wire 145 to the bridge pair of contacts 99 and 100 current momentarily flows from the battery 133 through the wires 132 and 146 to the contact ring 108 thence through the contact 99 through the contact arm 102 to the contact 100 and thence through the wire 144 to one end of the coil 141. The current then passes through the coil 141 and the wire 140 to the motor 66 and from the motor through the wires 139 and 135 to the battery thereby energizing the coil 141. When the coil 141 is energized it attracts the armature 148 on the arm 147 towards itself thereby engaging the contacts 143 and 149. Thereafter the current flows through the wires 132 and 150 to the arm 147 and through the contacts 143 and 149 to the wire 140 thereby retaining the coil 141 energized and at the same time operating the motor 66. As the motor 66 operates it rotates the shaft 69 which through the medium of the threads 72 moves the plate 63. As the plate 63 is thus moved it moves out of the path of one of the outer pins 59 into the path of the inner pins.

As the plate 63 moves out of the path of one of the outer pins which has been engaging it the spring 43 rotates the disk 33 until one of the inner pins 59 which represent the before mentioned selected station engages the plate 63 where-

upon the disk ceases to revolve whereupon the condenser being in the correct position to bring in the desired station the radio set will play that station. When the plate 63 has travelled into the path of the inner pins 59 the snap-over switch 76 is operated to reverse the motor field and in so doing breaks the electrical connections from the battery through the motor thereby breaking the circuit to the coil 141 whereupon the contact 149 is moved out of engagement with the contact 143 thus opening the circuit from the battery to the motor.

To automatically move the pins 59 upward after the stations have been played I provide a roller 160 which is supported in brackets 161 on the partition 16. When pins which have been moved downward pass the roller 160 the roller moves them upward to a position wherein they are above the upper edge of the plate 63 and consequently will not engage the plate when they are again in line with it.

For automatically moving the pins 59 downward again after they have been moved upward by a roller 160 I provide a reset device 162 (see Figs. 5 and 6). As shown the reset device 162 comprises a disk 163 freely mounted on a shaft 164 which is rotatably supported in bearings 165 mounted on the partition 16. On each side of the disk 163 I secure a hub 164' to the shaft 164 and on the hubs I provide a spring member 166 which in turn engages the sides of the disk 163. Also secured to the hubs 164' I provide an arm 168 the outer end of which includes projecting side fingers 169 and adjacent the outer end of the arm I provide thereon a roller 170.

The disk 163 engages the under-face of the disk 33 so as the disk 33 revolves in an operative direction the disk is rotated thereby which through the frictional engagement of the disk 163 and the spring members 166 moves the arm 168 upward to a position wherein the roller 170 engages the under-face of the disk 33 as shown in Fig. 6.

When it is desired to have the pins 59 automatically moved downward by the reset device 162 the pins 59 are turned so that the arms 61 thereon extend radially towards the opposite row of pins 59. Thus when the pins pass the reset device 162 the fingers 169 on the arm 168 engage the pin arms 61 and force them downward until they pass under the fingers 169. When it is not desired to have the pins 59 moved downward by the reset device 162 the pins 59 are turned so that the arms 61 thereon are moved out of the path of the reset device.

To automatically reset the buttons 93 to again bridge the contacts 99 and 100 I provide a reset device 172 which is similar to the reset device 162 except that the spring fingers and arm 173 which is similar to the arm 168 need be only on one side.

The device 172 includes a bracket 175 which is mounted on the disk 33 and the arm 173 thereof includes a finger 174 extending from one side thereof which is adapted to engage the fingers 63 of the buttons 93 and move them downward as previously described in connection with the reset device 162. Extending from the bracket 175 in a direction opposite to the arm 173 I provide an arm 176 on which a roller 177 is rotatably mounted. In operation the finger 174 moves the pins 93 downward to bridge the contacts 99 and 100 and then after the station controlled by that particular pin 93 plays and the disk 33 revolves a predetermined distance the roller 177

moves the pin 93 up. If it is desired not to have the buttons 93 automatically reset the buttons should be turned so that the arms 103 thereon are out of the path of the finger 174 of the reset device 172.

When the contact arm 118 of the clock switch bridges between the contact ring 108 and the contact 151 current flows from the battery 133 through the wires 135, 139 and 154 to the switch 49 which is closed thence through the switch and the wire 153 to the rewind motor 46. Then from the motor through the wire 152, the contact 151 and the contact arm 118 to the contact ring 108 and thence through the wires 146 and 132 to the 15 opposite side of the battery thereby causing the rewind motor 46 to operate. As the motor 46 is thus operated the disk 33 is rotated in a clockwise direction until the arm 51 on the disk 33 engages the arm 50 of the switch 49 and moves it to an open position thereby breaking the circuit to the rewind motor 49. When the disk 33 again rotates in an operative direction the arm 51 on the disk 33 moves out of engagement with the switch arm 50 whereupon the switch 49 again closes.

From the foregoing it will be apparent that I have invented a novel automatic station selector which is highly efficient in use and which can be economically manufactured.

Having thus described my invention, I claim:

1. In a station selector, a time switch, a rotatable disk, station selectors adjustably mounted on said disk, selector pins movable on said station selectors from an operative to an inoperative position, stop means, means operated by said time switch to project said stop means in the path of movement of the operative selector pins, means to lift said selector pins after said stop means has become disengaged therefrom and a reset arm mounted on each of said selector pins, a reset device, said reset arms being shiftable from operative to inoperative position, said reset arms in operative position being disposed in the path of movement of said reset device.

2. In a station selector adapted to operate in conjunction with a radio receiving set having a circuit including a condenser, means to vary the reactance of said circuit, said means including a disk, resilient means to normally urge said disk to rotate in one direction, a plurality of movable pins on said disk, a stop engaging an active one of said pins, electro-magnetic means to move said stop from engagement with one active pin and allow said disk to rotate a predetermined distance until the stop engages a second active pin to vary the reactance of said circuit a predetermined amount, means to energize said electromagnetic means at predetermined times, said energizing means including a source of electrical energy, a time switch including a plurality of segments successively connected with said source, and a plurality of switches each having one terminal connected with one of said segments, the other terminal of said switches being connected to said electro-magnetic means, whereby when the switch associated with the segment connected with said source is closed said electro-magnetic means is caused to operate.

3. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch

to connect said contacts consecutively and at regular intervals to the source of electricity, a time pin associated with each pair of spaced contacts, said time pins being rotatably and slidably mounted, each contact pin having a contact plate thereon adapted to bridge said contacts when the contact pin is in a depressed position, a disk rotatably mounted on said support, said disk having concentric slots therein, a standard fixed upon said support, a plurality of stationary condenser plates on said standard, a plurality of interspaced rotary condenser plates mounted on said disk, means to normally urge said disk in one direction, said disk having circumferentially spaced station selector buttons mounted in said concentric slots, a selector pin slidably mounted in each of said buttons, a stop plate, means to mount said stop plate for movement, and means whereby when a contact plate bridges its spaced contacts and said time switch functions to pass current through said contact said stop plate will be moved, said stop plate being movable from a position whereby it engages first one selector pin and then another selector pin.

4. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts to the source of electricity, a time pin associated with each pair of spaced contacts, said time pins being movably mounted, each contact pin having a contact plate thereon adapted to bridge said contacts when the contact pin is moved, a disk rotatably mounted on said support, a standard fixed upon said support, said disk having concentric slots therein, a plurality of interspaced rotary condenser plates on said standard, a plurality of interspaced rotary condenser plates mounted on said disk, said disk having a plurality of selector pins movably mounted in said concentric slots, a stop plate, means to mount said stop plate for movement, and means whereby when a contact plate bridges its spaced contacts and said time switch functions to pass current through said bridged contact, said stop plate will be moved, said stop plate being movable from a position whereby it engages one stop pin to a position where it engages another stop pin, whereby when said time pins are moved and said time switch functions said stop plate will reciprocate to alternately engage the moved selector pins.

5. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts to the source of electricity, a time pin associated with each pair of spaced contacts, said time pins being movably mounted, each contact pin having a contact plate thereon adapted to bridge said contacts when the contact pin is moved, a disk rotatably mounted on said support, a standard fixed upon said support, a plurality of stationary condenser plates on said standard, a plurality of interspaced rotary condenser plates mounted on said disk, said disk having concentric slots therein, a plurality of station selector buttons movably mounted in said slots, a selector pin movably mounted in

each of said buttons, a stop plate, means to movably mount said stop plate, and means whereby when a contact plate bridges its spaced contacts and said time switch functions to pass current through said bridged contact said stop plate will be moved from a position whereby it engages one stop pin to a position where it engages another stop pin, whereby when said time pins are moved and said time switch functions said stop plate will move to alternately engage the moved selector pins on the selector buttons.

6. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts consecutively and at regular intervals to the source of electricity, a time pin associated with each pair of spaced contacts, said time pins being rotatably and slidably mounted, each contact pin having a contact plate thereon adapted to bridge said contacts when the contact pin is in a depressed position, a disk rotatably mounted on said support, said disk having concentric slots therein, a standard fixed upon said support, a plurality of stationary condenser plates on said standard, a plurality of inter-spaced rotary condenser plates mounted on said disk, means to normally urge said disk in one direction, said disk having a plurality of station selector pins slidably mounted in said concentric slots, a stop plate, means to mount said stop plate for oscillating movement, and means whereby when a contact plate bridges its spaced contacts and said time switch functions to pass current through said contact said stop plate will be shifted, said stop plate being movable from a position whereby it engages one station selector pin to a position whereby it engages another station selector pin whereby when said time pins are moved and said time switch functions said stop plates will reciprocate to alternately engage selector pins.

7. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts consecutively and at regular intervals to the source of electricity, a time pin associated with each pair of spaced contacts, said time pins being rotatably and slidably mounted, each contact pin having a contact plate thereon adapted to bridge said contacts when the contact pin is in a depressed position, a disk rotatably mounted on said support, a standard fixed upon said support, a plurality of stationary condenser plates on said standard, a plurality of interspaced rotary condenser plates on said disk, means to normally urge said disk in one direction, said disk having a pair of concentric slots therein, a plurality of station selector buttons slidably mounted in said slots, means to secure said buttons in adjusted position, a selector pin slidably mounted in each of said buttons, a stop plate, means to mount said stop plate for oscillating movement, and means whereby when a contact plate bridges its spaced contacts and said time switch functions to pass current through said contact said stop plate will be shifted, said stop plate being movable from a position whereby

it engages a stop pin in the outer slot to a position where it engages a pin on the inner slot, whereby when said time pins are depressed and said time switch functions said stop plates will reciprocate to alternately engage the depressed selector pins on the outer and inner selector buttons.

8. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts to the source of electricity, a time pin associated with each pair of spaced contacts, said time pins being movably mounted, each contact pin having a contact plate thereon adapted to bridge said contacts when the contact pin is moved, a disk rotatably mounted on said support, a standard fixed upon said support, a plurality of stationary condenser plates on said standard, a plurality of interspaced rotary condenser plates mounted on said disk, means to normally urge said disk in one direction, said disk having a pair of concentric slots therein, a plurality of station selector buttons movably mounted in said slots, means to secure said buttons in adjusted position, a selector pin movably mounted in each of said buttons, a stop plate, means to mount said stop plate for oscillating movement, and means whereby when a contact plate bridges its spaced contacts and said time switch functions to pass current through said bridged contact said stop plate will be shifted, said stop plate being movable from a position whereby it engages a stop pin in the outer slot to a position where it engages a pin on the inner slot, whereby when said time pins are moved and said time switch functions said stop plate will reciprocate to alternately engage the moved selector pins on the outer and inner selector buttons.

9. In a station selector adapted to operate in conjunction with a radio receiving set having a circuit including a condenser, a base member, an annular support on said base member, a plurality of pairs of spaced contacts, a time switch, a source of electricity, means operated by said time switch to selectively connect pairs of said contacts to the source of electricity, a time pin associated with each pair of spaced contacts, each time pin having a contact plate thereon adapted to bridge said contacts when the time pin is moved in one direction, a reset arm on each contact pin, a disk rotatably mounted on said support, a condenser member on said disk, means to move said disk, said disk having a pair of concentric slots therein, a plurality of station selector buttons slidably mounted in said slots, means to secure said buttons in adjusted position, a selector pin movably mounted in each of said buttons, an outwardly extending reset arm on each of said selector pins each of said buttons including a shoulder adapted to be engaged by said selector reset arm, said shoulders being disposed so that the adjacent selector reset arm may be directed towards each other, a stop plate, means to mount said stop plate for oscillating movement, said means including a reversible motor, and means whereby when a contact plate bridges its spaced contacts and said time switch functions to pass current through the bridged contacts said motor will operate to shift said stop plate from a position where it engages a stop pin in one slot to a

position where it engages a stop pin in the other slot, whereby when said time pins are depressed and said time switch functions said stop plate will reciprocate to alternately engage the moved selector pins on the outer and inner selector buttons.

10. In a station selector adapted to operate in conjunction with a radio receiving set having a circuit including a condenser, a base member, an annular support on said base member, a plurality of pairs of spaced contacts, a time switch, a source of electricity, means operated by said time switch to selectively connect pairs of said contacts to the source of electricity, a time pin associated with each pair of spaced contacts, each time pin having a contact plate thereon adapted to bridge said contacts when the time pin is moved in one direction, a reset arm on each contact pin, a disk rotatably mounted on said support, a condenser member mounted on said disk, means to move said disk, said disk having a pair of concentric slots therein, a plurality of station selector buttons slidably mounted in said slots, means to secure said button in adjusted position, a selector pin slidably and rotatably mounted in each of said buttons including a shoulder adapted to be engaged by said selector reset arm, said shoulders being disposed so that the adjacent selector reset arm may be directed towards each other, a stop plate, means to mount said stop plate for oscillating movement, said means including a reversible motor, and means whereby when a contact plate bridges its spaced contacts and said time switch functions to pass current through the bridged contacts said oscillating means will shift said stop plate, whereby when said time pins are depressed and said time switch functions said stop plate will reciprocate to alternately engage the depressed selector pins on the outer and inner selector buttons.

11. In a station selector adapted to operate in conjunction with a radio receiving set having a circuit including a condenser, a base member, an annular support on said base member, a plurality of pairs of contacts spaced circumferentially about said support, a time switch, a source of electricity, means operated by said time switch to connect said contacts consecutively and at regular intervals to the source of electricity, a time pin associated with each pair of spaced contacts,

said time pins being rotatable and slidably mounted, each time pin having a contact plate thereon adapted to bridge said contacts when the time pin is in a depressed position, a reset arm on each contact pin, a disk rotatably mounted on said support, a standard fixed upon said support, a plurality of stationary condenser plates mounted on said disk, means to normally urge said disk in one direction, means to reset said urging means, said disk having a pair of concentric slots therein, a plurality of station selector buttons slidably mounted in said slots, means to secure said buttons in adjusted position, a selector pin slidably and rotatably mounted in each of said buttons, an outwardly extending reset arm on each of said selector pins each of said buttons including a shoulder adapted to be engaged by said selector reset arm, said shoulders being disposed so that the adjacent selector reset arm may be directed towards each other, a stop plate, means to mount said stop plate for oscillating movement, said means including a reversible motor, and means whereby when a contact plate bridges its spaced contacts and said time switch functions to pass current through the bridged contacts said motor will operate to shift said stop plate from a position where it engages a stop pin in one slot to a position where it engages a stop pin in the other slot, whereby when said time pins are depressed and said time switch functions said stop plate will reciprocate to alternately engage the depressed selector pins on the outer and inner selector buttons.

12. In a station selector, a time switch, a member movable to different positions to tune in different stations, station selectors adjustably mounted on said member, selector members movable on said station selectors from an operative to an inoperative position, stop means, means operated by said time switch to project said stop means in the path of movement of the operative selector members, means to shift said selector means after said stop means has become disengaged therefrom and a reset member mounted on each of said selector members, a reset device, said reset members being shiftable from operative to inoperative position, said reset members in operative position being disposed in the path of movement of said reset device.

ROSCOE BOWERMAN.
